UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

FURNACE.

1,243,872.

Specification of Letters Patent. Patented Oct. 23, 1917.

Application filed January 29, 1917. Serial No. 145,209.

To all whom it may concern:

Be it known that I, HERMAN A. POPPENHUSEN, a citizen of the United States, residing at Hammond, in the county of Lake 5 and State of Indiana, have invented a new and useful Improvement in Furnaces, of which the following is a specification.

This invention relates to improvements in furnaces, and more particularly to the 10 construction of a device associated with a grate of the traveling chain type and adapted, among other things, to retard the fuel at the rear of the grate, and so arranged to permit the same to be moved to permit access to the rear portion of the fuel bed for 15 the purpose of inspection or cleaning.

In furnaces of the mechanical stoker type, employing traveling chain grates, it is desirable to provide a transversely extending 20 member (preferably water cooled to prevent adhesion of the ashes thereto) at the rear of the grate and spaced above the surface thereof, said water cooled member, or "water-back" as it is called, serving to 25 regulate the thickness of the fuel bed, by defining the discharge opening, through which the ashes are discharged from the grate, and in retarding the upper layer of the fuel until it is completely consumed and reduced to 30 ash before being discharged.

Furthermore, in the operation of furnaces of this type, it is often desirable to clean or otherwise attend to the fire, by means of suitable tools, this being ordinarily impossible 35 in a furnace of the mechanical stoker type, because of the closed construction at the front of the furnace. It is proposed, therefore, to provide a movable gate or retarding member, coöperating with a fixed 40 retarding member or water-back, said gate or retarding member being capable of movement in a direction to open the space above the grate, thereby affording access to the fuel bed from the rear end of said grate, and to permit a person to operate the gate 45 member and to attend to the fuel bed, by means of tools, access being had to the combustion chamber by the use of a separate rear compartment, embracing a partition 50 wall located rearwardly of the grate and provided with a door adapted to be opened when access to the gate member and grate surface is desired.

The details of construction whereby the objects of the invention are accomplished, 55 are hereinafter fully described and illustrated in the accompanying drawings, wherein—

Figure 1 is a view in longitudinal section through the rear portion of the combustion 60 chamber and grate of a furnace, and embodying the features of the invention;

Fig. 2 is a detail view in section, showing the gate member in open position; and

Fig. 3 is a view in cross-section taken on 65 line 3—3 of Fig. 1, showing the principal parts in elevation.

Referring to the drawings, there are illustrated only such parts of the furnace as pertain to the invention, it being understood 70 that a furnace to which the improved device is applicable is of the standard construction, embracing side walls 9, 9, of brick, the front wall inclosing a combustion chamber in the forward part of the furnace, 75 wherein is mounted a grate 10, preferably of the endless chain type, the grate being carried by rollers and sprocket wheels at the front and rear ends, there being provided suitable actuating mechanism for mov- 80 ing the grate. As illustrated in the drawings, the rear portion of such grate 10 is shown, the same being mounted on sprocket wheels 11, carried upon a transverse shaft 12, journaled in a suitable frame structure 85 13. Immediately above the rear end of the grate and spaced a considerable distance therefrom, is a cross-wall 14, extending transversely of the combustion chamber and forming the rear wall thereof. The cross- 90 wall is constructed of brick and supported upon a series of longitudinal and parallel beams 15, of I-section, which in turn rest upon another series of parallel cross-beams 16, of I-section, extending transversely be- 95 low the cross-wall and suitably mounted at their ends in the side walls of the furnace. Above the combustion chamber and extending throughout the length of the furnace is the boiler space, containing the steam boiler 100 (a part 17 being shown in Fig. 1). At the rear of the combustion chamber and below the cross-wall 14 is a vertical partition wall 18, which separates said combustion chamber from the space behind said partition 105 wall, such space being preferably inclosed

- by walls to form a compartment which may be entered from the exterior of the furnace. The partition wall is provided with openings, which are normally closed by vertically swinging doors 19, 19, extending throughout the height of said walls. The doors are supported by means of hinges 20 to the frame or partition wall 18 and locked in closed position by means of suitable locks 21.
- Extending transversely of the combustion chamber and immediately below the front margin of the cross-wall 14 are two water-circulating tubes 22 and 23, forming a "water-back" or water cooled member, adapted to prevent the formation of clinkers at the ash discharge opening and, further, to act as fuel-retarding members, as will herein-after be pointed out. The upper tube 22 is located adjacent to the under surface of the cross-wall 14, in close proximity to the front ends of the longitudinal supporting beams 15, and the lower tube 23 is located vertically below the upper tube 22 and spaced a short distance above the surface of the grate, there being provided a vertical space between the tubes and between the lower tube 23 and the grate surface, the latter forming the discharge opening for the ashes.
- Mounted immediately behind the tubes 22 and 23 is the swinging gate or fuel-retarding member, comprising members as follows: A transverse bar 24, of T-form, extends transversely of the combustion chamber just below the beams 15 and to the rear of the upper tube 22, said bar being preferably secured to the lower flanges of said beams and provided with a downwardly depending flange, slightly curved in the direction of said tube and terminating just above the lower surface thereof. Depending from the lower margin of said bar 24 are a plurality of gate members or plates 25, 25, preferably two in number, pivotally connected to the bar 24 by a suitable number of hinges 26 along their adjacent margins. These plates are arranged end to end, and extend transversely between the side walls of the furnace, and in reality are but independent sections or units of a single movable gate or retarding member.
- Referring to the construction of the gate members proper, 25, 25, the same comprise vertically arranged, L-shaped plates, provided at their lower margins with flanges 27, 27 extending at right-angles to the plates and forwardly in the direction of the plane of the tubes 22 and 23, said flanges preferably having short upturned flanges along their outer edges, which bear flatwise against the rear surface of the lower tube 23. When the plates are in their vertical or closed positions, they form a closure or wall immediately behind the tubes and close the space therebetween, that is, the entire

vertical space between the grate surface and the cross-wall 14, with the exception of the opening below the lower tube, which forms the discharge opening of the ashes.

For the purpose of opening the space normally closed by the gate members, the following devices are employed for retaining them in open position and for holding the plates in closed position against the pressure exerted upon the plates by the fuel. Pivotaly mounted upon the under surface of the cross-wall 14, and at a point rearwardly of the plates, are plate-locking members 28, 28, there being preferably provided one for each plate. Each of these locking members consists of two pivotally connected links 29 and 30, the upper link having pivotal connection at its upper end with a suitable bracket 31, connected to the upper side of a beam 15, the lower link 30 being pivotally connected at its opposite end. At the adjacent connected ends of each link are provided integral lugs or ears 32, 32 extending at right-angles to the links from the sides thereof facing the plates 25, 25, and serving a purpose that will be presently disclosed. To lock or hold the plates in vertical or closed position, the links preferably occupy a position of substantial alignment with each other, and are inclined forwardly and downwardly at an angle of 45° toward the plates, which are provided upon their rear faces and adjacent their lower margins with lugs 33, 33, which are engaged by the free ends of the lower links 30. In this position the links form a rigid inclined brace member, serving to hold the plates rigidly in contact with the tube 23, the ears 32, 32 making the links rigid by preventing the breaking or flexing of the links in a downward direction. To release the plates, the brace or locking member is removed, by breaking or flexing the links at the center joint, by striking them on the under side with a suitable tool or otherwise, thus disengaging the free end of the links from the retaining lugs 33 and allowing the links to drop into a vertically depending position, as shown in Fig. 2. The plates are now free to be swung rearwardly and upwardly, this being accomplished from the rear and through the open doors of the compartment at the rear of the furnace, each plate being preferably provided with a handle or bar 34 attached to the rear face of the plates and extending downwardly and rearwardly therefrom. In the swinging of a plate upwardly, above the ears 32, 32 of the depending links, the uppermost ear acts as a hook, which engages the edge of the flange thereof, thereby retaining the plate in open position. By disturbing the links slightly, the plate may be dropped into closing position and the links readjusted to form the brace, as before.

It has been suggested that the tubes form a water-back or water-cooled member, acting to partially define or restrict the discharge opening for the ashes and, by reason of 5 the cooled surfaces, prevent the formation of clinkers. The space between the links, however, provides an opening, through which fuel as well as a considerable amount of heated gases can escape. Hence it is de- 10 sirable under operating conditions to seal or close this space between the tubes, not only to prevent the escape of the gases and fuel, but also to aid in retarding the layers of fuel above the discharge opening and for 15 the purpose hereinbefore pointed out. The plates are especially designed to prevent their being burned out by the hot fuel, in that they are spaced from the tubes by the provision of the lower marginal flange, 20 which also provides a pocket which becomes filled with dead ash, thus forming an effective protection from the heat.

The space between the tubes is furthermore available for the purpose of inspecting 25 or inserting tools therethrough for attending to the fire, this being done from the rear compartment and through the opening of the doors thereof, while the furnace is in operation. It is for this reason that the 30 plates are adapted to be swung upwardly, so as to open the space between the tubes, this being done, as before set forth, by any suitable tool at hand and without exposure to the heat of the furnace. It is preferable 35 to form the movable gate members in two or more parts or sections for the obvious reason that it enables one portion of the fuel bed to be inspected or treated without disturbing the remaining portions, or un- 40 necessarily opening the entire space simultaneously.

In conjunction with a rear compartment adapted to permit access to the combustion chamber, in the absence of convenient means 45 from the front and exterior of the furnace, the gate members and associated parts constitute a conveniently operable device, serving to seal the space at the rear of the grate and as a retarding member under normal 50 conditions of operation, and having the advantage of being movable to permit the space or opening closed thereby to be used for inspecting or otherwise attending to the fire.

55 The features embodying the invention are more specifically pointed out in the appended claims.

I claim as my invention:

1. In a furnace, the combination of a 60 grate, a wall extending transversely above said grate, a fixed fuel retarding member spaced from the surface of said grate and forming a transverse opening between said fuel retarding member and said wall, and a 65 gate member mounted adjacent said wall

and movable into and out of contact with said fuel retarding member, to open and close said opening.

2. In a furnace, the combination of a 70 grate, a wall extending transversely above the surface of said grate, a water circulating tube mounted between the surface of the grate and said wall, and a gate member pivotally mounted above the grate and adapted to be swung into and out of contact with 75 said tube, to open and close the space between the same and said wall.

3. In a furnace, the combination of a 80 grate, a cross-wall above the rear end of the grate, a water-circulating tube extending transversely of said grate between the same and said wall, and a gate member pivotally mounted upon said wall and extending downwardly behind and in contact with said tube and adapted to be moved into and out 85 of position to open and close the space between said tube and wall.

4. In a furnace, the combination of a 90 grate, a cross-wall spaced above the rear of said grate, a fixed fuel-retarding member mounted in the space between said wall and grate surface and forming therebelow an ash discharge opening, a gate member comprising a vertical plate pivotally mounted above said fixed member and adapted to be 95 swung into and out of contact with said fixed member to open and close the space above the same, and a removable brace member adapted to hold said plate in closed position. 100

5. In a furnace, the combination of a traveling chain grate, a fixed fuel-retarding member spaced above the grate and forming an intermediate ash discharge opening, a movable fuel-retarding member, comprising 105 a plate pivotally mounted along its upper margin above said fixed member and extending downwardly in contact along its lower margin with the same, and means for retaining said plate in contact with said fixed member, comprising a removable brace member mounted rearwardly of said plate. 110

6. In a furnace, the combination of a traveling chain grate, a cross-wall spaced above the rear of said grate, a fixed water-circulating tube mounted in the space between said wall and grate surface and forming therebelow an ash discharge opening, and a gate member comprising a vertical plate pivotally mounted at its upper margin above said tube and provided along its lower margin with a flange bearing against the rear surface of said tube. 115

7. In a furnace, the combination of a traveling chain grate, a cross-wall extending 125 transversely above the rear portion of the grate, a fixed fuel-retarding member spaced between the under surface of said wall and the grate and forming an ash discharge opening therebelow, a movable fuel-retard- 130

ing member comprising a plurality of transversely arranged plates pivotally connected beneath said wall and extending downwardly behind and terminating in contact with said fixed member, and locking means for retaining said plates in contact with said fixed member.

In testimony that I claim the foregoing

as my invention, I affix my signature in the presence of two witnesses, this 13th day of 1 January, A. D. 1917.

HERMAN A. POPPENHUSEN.
